LOOM MAINTENANCE INDICATOR

Coyt E. Murray, 1805 Echo Lane, Gastonia, N.C.

Filed Feb. 18, 1965, Ser. No. 83,910

Term of patent 14 years

(Cl. D52—1)

Fig. 1.

Fig. 2.

FIGURE 1 is a front elevation of the loom maintenance indicator as mounted on a loom with a portion of the frame of the loom and the mounting bolt shown in dotted lines for purposes of illustration only;

FIGURE 2 is a side elevation of the loom maintenance indicator looking at the right hand side of FIGURE 1, but on a reduced scale, and also showing the loom frame and mounting bolt in dotted lines.

The back of the loom maintenance indicator is plain and the side not shown is like the side shown in FIGURE 2.

I claim:

The ornamental design for a loom maintenance indicator, as shown and described.
